UNITED STATES PATENT OFFICE.

JOHN P. GALLAGHER, OF JERSEY CITY, NEW JERSEY, ASSIGNOR TO MAGOR CAR CORPORATION, OF NEW YORK, N. Y., A CORPORATION OF DELAWARE.

INTERMEDIATE-SILL REINFORCEMENT.

Application filed May 16, 1924. Serial No. 713,679.

To all whom it may concern:

Be it known that I, JOHN P. GALLAGHER, a citizen of the United States, and resident of Jersey City, in the county of Hudson and State of New Jersey, have invented certain new and useful Improvements in Intermediate-Sill Reenforcements, of which the following is a specification.

The invention relates in general to an improved form of car center sill construction for use in connection with freight, passenger and other forms of cars when formed of metal, and/or wood, and the invention specifically relates to a metallic reenforcement for car underframes which have their center and other sills formed wholly or in part of wood.

This application constitutes a development of the disclosure in my copending applications for combined draft arm and center sill reenforcement, Serial No. 595,461, filed October 18, 1922, and center sill reenforcement, Serial No. 698,738, filed March 12, 1924, and the present disclosure is to be regarded as another embodiment of the inventive features disclosed and claimed in these two pending applications.

In the latter of the above identified applications it was pointed out that the old wooden underframe construction did not have sufficient structural strength to meet modern service requirements, such as the requirements of the Master Car Builders that the steel car sills have at least 30 square inches sectional area. It has been suggested to reenforce the wooden underframe of the old cars and in the above applications it was suggested to insert a pressing at each end of the car to armour the center sills and which pressing includes outstanding flanges which lap the bolsters and provide both gusset plates and diagonal strain transmitting braces. It was indicated that these pressings at each end of the car might be connected by a mid-section or the reenforcement might extend as one or more pieces from end to end of the car to provide a steel back-bone to the wooden underframe.

It was also suggested in the later filed

application that the required reenforcement be formed in part by the intermediate and other sills, wooden or otherwise, already in the car underframe structure to be reenforced.

In the specific embodiment selected for illustration in this pending application the reenforcement at the car end was shown to be a pressing fitted between the center sills and provided with outstanding flanges secured to the intermediate sills so that the intermediate sills, at least where they crossed the bolster, would become part of the reenforcement.

The problem of properly reenforcing these wooden underframes economically is complicated by the necessity of avoiding the formation of bulky parts to any reenforcing structure and the necessity of avoiding other structural parts which are already located on or adjacent the underframe and disposed in accordance with standard practice. However, it is generally true that the intermediate wooden sills between the bolsters are free of obstructions.

Accordingly the present disclosure may be regarded as a carrying forward of the idea expressed in the preceding applications and features the utilization of the cross-section of material in the wooden intermediate sills to make up part of the cross section of material required to meet present service conditions.

The primary object of the present invention is to provide a simple form of supplemental reenforcing underframe structure for strengthening and reenforcing the sills, both center and intermediate, between the bolsters so that in addition to the steel back-bone previously featured there will be provided an outer sill reenforcement secured and connected to the end reenforcements so as to form a steel skeleton frame which together with the parts reenforced will provide a composite underframe of a strength sufficient to meet modern requirements.

In general the invention features a fabricated reenforcement which will distribute strains received at either end of the car out-

wardly to the adjacent bolsters, and either therethrough or independently thereof, to both the intermediate and other outer sills as well as the center sills, all of which are 5 reenforced to thereby receive and distribute these strains. Differently expressed the invention contemplates the utilization of the outer sills when reenforced between the bolsters as part of the necessary structural 10 strength of the car underframe.

Various other objects and advantages of the invention will be in part obvious from an inspection of the accompanying drawings and in part will be more fully set forth in 15 the following particular description of one form of mechanism embodying my invention, and the invention also consists in certain new and novel features of construction and combination of parts hereinafter set forth 20 and claimed.

In the accompanying drawings:—

Figure 1 is a plan view of a wooden car underframe equipped with a preferred embodiment of the invention and with parts at 25 the center of the car broken away to save space; and

Figure 2 is a transverse sectional view taken just in rear of the bolsters and taken on the line 2—2 of Figure 1 looking in the 30 direction indicated by the arrow.

In the following description and in the claims, parts will be identified by specific names for convenience of expression but they are intended to be as generic in their application to similar parts as the art will permit. 35

In the drawings there is shown a wooden car underframe formed of longitudinally extending members, comprising a pair of transversely spaced apart wooden center sills 10 and 11, side sills 12 and 13, and intermediate sills 14 and 15 and transversely extending 40 members including end sills 16 and bolsters 17. There is also disclosed certain other structural features such as buffer blocks 18.

It is understood that this showing is intended to represent conventional structures and to disclose a type of wooden underframe which is to be reenforced by the metallic 45 construction particularly forming the subject-matter of this application.

In the form herein illustrated the center sill reenforcement comprises three major and two minor units formed of metal plate pressings. Of the major pressings there is intended to be used two end members each extending from one of the end sills past the adjacent bolster and a connecting member disposed between the end members and fastened at each end to the end members by means of tie plates which constitute the two minor 50 units and are preferably pressings.

Referring to either of the end members, 21, there is illustrated a single metal plate pressing having a length sufficient to extend 55 from the end sill to the bolster and prefer-

ably across the bolster for a distance equal to or less than the distance from the bolster to the end sill. The pressing is of a length to extend towards the center of the car from the bolster a distance approximately more 70 than one-half of the distance between end sill and bolster. The central portion of the pressing is bent longitudinally into a channel 22, inverted U-shaped in cross-section and of a size to fit between the inner faces 75 of the center sills and acting to form a thrust beam at the adjacent end of the car underframe. This beam includes a pair of vertically disposed webs 24, a top flange 25 and outstanding bottom flanges 26 which project integrally from the lower edges of each of the webs 24 and coact therewith to provide right angle seats for the wooden center sills 10 and 11.

The flanges 26 are extended on each side 85 beyond the outer faces of the adjacent center sills to provide horizontally disposed plates. Each plate is of maximum width along the bolster and extends practically to the adjacent sill 14 or 15. The plate coacts 90 with the adjacent upstanding web 24 to form an angle pressing which in addition to providing a seat for the wooden sill will function as a diagonal strain transmitting brace 95 to distribute shocks received at the center 100 of the end sill and to convey the same to the portions of the bolster to the outside of the center sills.

The general effect of the construction as thus far described will be to effect a transference and distribution of shocks at the center of the end sill in direct lines to the central portion of the bolster and along outwardly divergent lines to the portions of the bolster outside of the center sill construction. 105 The portion of the flanges which extend horizontally beyond the center sills are fastened to the bolster by means of rivets 29 and in this way there is provided a plate 110 which functions as the usual gusset plate between the center sill construction and the bolster.

The central unit 30 connecting the end pressings 21 resembles the end pressings in 115 outline and dimension, except that it is not provided with the gusset plate forming extensions. This part of the construction is simply a one-piece channel shaped member, preferably a pressing, inverted U-shaped in cross section and provided with outstanding 120 flanges 31. However, this part as well as the end pressings 21 may obviously be formed of two Z members riveted together. The ends of the central pressing are secured to the adjacent end pressings by means of tie plates 32 which extend across the joints between the units and are fastened by rivets 125 33. In the present disclosure this tie plate corresponds in cross section to the central member, except that it is of correspondingly 130

smaller size so as to fit in the trough or channels of the members to which they are attached.

In the latter of the two previous applications the reenforcing pressings disclosed in the first application was continued laterally so as to include the portions of the intermediate sills 14 and 15 at the bolsters as parts of the adjacent pressing and thus add the cross-section of material in the intermediate sills at the bolster to make up the necessary cross-section of material in such structures required by the Master Car Builders. This was attained by securing the 15 gusset plate forming flanges of the pressing to the intermediate sills in some approved way, several methods of attachment being disclosed. Instead of securing the pressings to the unenforced intermediate sills the 20 present disclosure features the securing of the pressings, either directly or indirectly through the bolsters and similar parts, to certain metallic reenforcements designed to strengthen the intermediate sills. For this 25 purpose each of the intermediate sills is provided with a Z-shaped reenforcing member 33. This member includes an upstanding flange 34 fitted against the inner face of its associated sill and secured thereto by 30 horizontal bolts 35. The member also includes a horizontal flange 36 which engages the underside of the sill.

In order to provide additional cross-sectional area of material, to brace the member 35 vertically and to lower the center of mass of the same, the horizontal flange 36 is provided at its outer edge with a depending rib or flange 37 which extends as far as desired below the sills and preferably flush 40 with the outer side faces of the same. As the pressings 21 are secured to the bolsters 17 and the intermediate sills are secured to the bolsters it is not necessary to secure the reenforcements 33 directly to the pressing. 45 However, this may be done following conventional practice in securing metal parts and it is herein suggested that an angle 38 be positioned above the bolster and be secured by rivets 39 to the flange 26 and by 50 horizontal bolts 40 which pass through the angle, through the flange 34 and through the adjacent sill.

As the strains received from the adjacent central portion of the end sills are directed 55 through the diagonal braces to the portions of the intermediate sills at the bolsters there is no particular necessity of reenforcing the portion of the intermediate sills between the bolster and its adjacent end sill and therefore the Z-shaped reenforcing plate 33 is shown to extend only from bolster to bolster and preferably overlaps both bolsters.

The end pressings, either with or without the intermediate center sill reenforcement 60 31, coacts with the intermediate sill re-

enforcements 33, to provide an underframe reenforcement which acts to receive and to transfer centrally imposed strains diagonally and outwardly towards the intermediate sills and therethrough towards the opposite 70 end of the car.

A certain proportion of these strains are transferred laterally through the bolsters towards the side sills 12 and 13 and it is suggested that these side sills be reenforced 75 between bolsters by Z-reenforcing shapes 41 secured thereto by bolts 42 as has been suggested in the case of the intermediate sill.

In the preceding application it was suggested to corrugate the horizontal extending plates forming the reinforcements in order to obtain the maximum resistance to bending with the use of the least possible amount of material. In this disclosure it is suggested that the corrugations 43 be depressed 80 so as to extend downwardly and in this way lower the center of mass of each of the horizontally extending plates and thus tend, particularly in the case of the top flange 25, to lower the line of thrust through the U-beam between the sills towards the central horizontal plane of the wooden center sills. 85

By means of a reenforcing construction such as is herein disclosed it is possible to provide the old wooden car underframe with sufficient cross-section of reenforcement to meet modern requirements and at the same time to attain this result while featuring economy in the amount of metal used and economy in the cost of constructing the reenforcement as well as the cost of installing the same in place. 95

It is simply necessary to stamp the different reenforcements to the desired dimensions to fit any particular set of car underframes, bolt the same in position through bolt holes many of which are already in the structure to be reenforced and the others of which can be easily formed. 100

Certain of the wooden or composite structural parts which have heretofore been ignored in estimating the strength of the center sill construction are now brought into the figuring of the strength of the underframe. The several portions of the old 110 underframe at the bolsters, at the draft lugs and at the center of the underframe as well as the associated parts are tied together so as to mutually reenforce and brace each other and thus form a rugged part wood 115 and part metal underframe which meets modern requirements of structural strength not only at the bolster but also at any place along the length of the underframe between the bolsters. 120

Having thus described my invention, I claim:

1. In a car underframe, the combination of a pair of center sills, a pair of intermediate sills, a pair of side sills, and end sill 130

- and a bolster, of a reenforcement comprising a structural unit having a central part fitted between the center sills to reenforce the same, having outstanding flanges constituting gusset plates on each side of the center sill, overlapping the bolster, and extending longitudinally therefrom to the end sill to form strain braces, means for tying the gusset plates to the vertical sides of the intermediate sills whereby the unit acts as a spacing member for securing the intermediate sills in fixed relation to the center sills and whereby both the center and intermediate sills are united and mutually reenforced and metallic means secured by said tying means and engaging the intermediate sills from said bolster towards the center of the car for reenforcing the intermediate sills.
2. In a device of the class described, the combination with a car underframe, complete per se, and including a pair of wooden center sills and a pair of intermediate sills, said sills collectively having a sectional area of material of a strength less than that equal to thirty square inches of metal, of a structural metal unit constituting a reenforcement secured to both of the pair of center sills and extending along the center sills between bolsters and secured to the pair of intermediate sills, said metal reenforcement having a sectional area less than thirty square inches and coacting with the sills to provide a sectional area at least equal to thirty square inches of the metal.
3. In a car underframe, the combination with a center sill, other sills on opposite sides of the same and a bolster, of a single structural unit secured to the bolster and provided with means for tying the sills in their preset relative position and provided with parts for reenforcing the center sills and with other parts for reenforcing the other sills.
4. In a car underframe, the combination with a pair of center sills, a pair of intermediate sills cooperatively associated to form a car underframe and a pair of bolsters, of structural units at each end of the underframe provided with means fitting between and reenforcing the center sills and other means engaging the intermediate sills and extending between the bolsters for reenforcing the central portion of the underframe between the end units.
5. In a device of the class described, the combination with a car underframe complete per se and including wooden center sills and other sills, which collectively have a sectional area of material less than a prescribed strength of sectional area, of a metal reenforcement for both the center sills and said other sills, said metal reenforcement including members engaging said other sills at the center of the car and having a sectional

area of material sufficient to supplement said wooden center and other sills and coacting therewith to provide the prescribed strength of sectional area.

6. In a car underframe, the combination of a pair of wooden sills and a pair of outer sills to be reenforced, end sills and bolsters, of a fabricated metallic reenforcement including similar end units, each constituting a combined brace, center sill reenforcement and gusset plate structure, a central unit constituting a center sill reenforcement and connected at opposite ends to the end units, and means for reenforcing the outer sills, said last named means secured at opposite ends to the end units.

7. A fabricated car underframe reenforcement formed of five major units comprising two similar end units, each constituting a combined brace, gusset plate and center sill reenforcement for the part of the center sills adjacent the contiguous bolster, a connecting central unit constituting a reenforcement for the central part of the center sills and a pair of outer members extending between the bolsters constituting outer sill reenforcements for the portions of the outer sills between the bolsters.

8. A car underframe reenforcement including four major units, two of the units at opposite ends of the reenforcement being similar in shape and each provided with outstanding flanges constituting combined strain transmitting braces and gusset plates and the other two units secured at opposite ends to the gusset plate forming flanges and constituting outer sill reenforcements.

9. In a car underframe, the combination with a bolster, its adjacent end sill, a center sill and an outer sill, of a reenforcement for the portion of the center sill between the end sill and the bolster and including a horizontally disposed gusset plate projecting laterally from the center sill and reenforcing members for the outer sill extending from the gusset plate towards the center of the car.

10. A reenforcement for a car underframe comprising a pair of gusset plates provided with means for securing the same to the center sill and a connecting member secured at opposite ends to the gusset plates in laterally spaced relation to the center sills.

11. In a car underframe, the combination of wooden center sills, wooden outer sills, means at each end of the car for reenforcing the center sills from an end sill across the adjacent bolster and means for reenforcing the outer sills between the bolsters.

12. In a car underframe, a metal reenforcement including a central channel shaped portion with an outstanding flange, the web of the channel shaped portion and said flange provided with depending corrugations.

13. In a car underframe, a sheet metal reinforcement including a horizontally disposed plate provided with corrugations and in which the corrugations depend from the 5 plane of the plate.
14. A metallic reenforcement for car underframes including a corrugated plate

structure in which the corrugations extend downwardly from the plate thereby to lower the center of mass of the plate.

10

Signed at New York city, in the county of New York and State of New York, this 15th day of May, A. D. 1924.

JOHN P. GALLAGHER.
